UNITED STATES PATENT OFFICE.

WILLIAM E. CRAFT, OF ANDERSON, INDIANA, ASSIGNOR OF ONE-FIFTH
TO W. H. LARMORE, OF ANDERSON, INDIANA.

PRICE-SCALE.

No. 828,397.

Specification of Letters Patent.

Patented June 12, 1906.

Application filed August 25, 1905. Serial No. 275,802.

To all whom it may concern.

Be it known that I, WILLIAM E. CRAFT, a citizen of the United States, residing at Anderson, in the county of Madison, State of Indiana, have invented certain new and useful Improvements in Price-Scales; and I do hereby declare the following to be a full, clear, and exact description of the invention, such as will enable others skilled in the art to 10 which it appertains to make and use the same.

This invention relates to scales, and more particularly to price-scales, and has for its object to provide a scale of this kind which will 15 be arranged to indicate the value of articles weighed thereupon and which may be manufactured at a low figure.

Other objects and advantages will be apparent from the following specification, which 20 describes an embodiment of the present invention.

In the drawings forming a portion of this specification, and in which like characters of reference indicate similar parts in the several 25 views, Figure 1 is a front elevation of the present invention. Fig. 2 is a longitudinal section of the chart-casing. Fig. 3 is a top plan view. Fig. 4 is an edge view, the chart-casing being broken away to show the arrangement of the rolls.

Referring now to the drawings, there is shown a pair of scales comprising a scoop-receiving base 5, an upright standard 6, located at the rear of the base and at one side thereof, 35 and a horizontally-extending casing 7, secured at one end to the upper end of the standard and supported at its other end by a suitable upright 8. A scale-arm 9 is pivoted at one end, as shown, this end carrying an upwardly-extending loop 10, which is engaged with a loop 13, carried by the casing, and a vertical rod 14 is pivoted to the scale-arm adjacent to the loop 10 and between this loop and the plane of the standard 6. The arm 9 40 extends considerably beyond the opposite side of the loop 10 of the rod 14, and it is graduated, as shown at 9'. The rod 14 is connected at its lower end with a vertically-movable platform 11, arranged in the usual 45 manner, the connection being such that downward movement of the platform results in upward movement of the free end 12 of the scale-arm. Engaged with the arm at this

end 12 there is a weight-receiver 15 of the usual type.

Below the scale-arm 9 and parallel therewith there is a supplemental arm 16, connected with the arm 9 by upwardly-extending portions 17, the supplemental arm 16 being graduated and having a sliding poise 18 55 mounted thereupon, a similar poise 19 being slidably mounted upon the arm 9, and these poises are provided with pointers 18' and 19', respectively arranged to indicate different points upon the scale-arms.

Mounted within the casing 7 there are a pair of longitudinally-extending chart-rollers 20 and 21, respectively, which lie in spaced relation and which have gears 22 and 23 at their ends which lie away from the standard 6. A stem 24 is engaged in the end of the casing adjacent to the gears, this stem having a gear 25 at its inner end lying between and meshing with the gears 22 and 23. At its outer end the stem 24 is provided with a 70 thumb-piece 26, by means of which it may be rotated to revolve the shafts 20 and 21.

Secured at its ends to the shafts there is a chart 27, having series of figures marked thereon which extend longitudinally of the 80 casing 7, and the casing is provided with an opening 28 in its forward face, which is formed longitudinally therein and through which one of the series of figures may be seen, it being apparent that the rollers may be revolved 85 to bring the different series into registration with the opening successively.

Each series of figures marked upon the chart 27 consists of a plurality of price-marks beginning at the side of the chart lying adjacent to the pivoted end of the scale-arm and increasing toward the free end 12 of the scale-arm, these price-marks corresponding with the graduation of the scale-arm to indicate the value of different amounts of merchandise which might be placed upon the scale, and the poise 19 has an upwardly-extending indicator 19^a, arranged to indicate the different price-marks of the chart. It will be understood that the different series of price-marks are arranged to indicate the value of merchandise having different values per pound, and the series shown in the drawings is for merchandise at the value of five cents per pound. It will thus be seen that the numeral "5" lies in position for indication by 95 100 105

the indicator 19^a when the indicator 19' lies above the one-pound mark upon the scale-arm 9, the other price-marks lying above their respective marks upon the scale-arm 5 and between the pound-marks of the scale-arm. The chart has the prices for fractions of a pound. It will thus be seen that the poise 19 may be moved to balance the scales and that the indicator 19' will then indicate 10 the weight of matter upon the platform 11, while the indicator 19^a will indicate the price of such matter.

When matter upon the platform 11 is so heavy as not to be balanced by the poise, 15 weights A may be disposed upon the weight-holder 15, and it will be seen that when this is the case the numbers upon the chart will no longer indicate directly the price of the matter weighed. For this reason a second 20 series of figures B is marked upon the chart at one end of each of the series of price-marks, these series B consisting of upper numbers B', indicating the denominations of the weights A which may be used, and of lower 25 numbers B'', the latter indicating the value of a sufficient amount of merchandise to balance the weights indicated by the figures B', and it will be understood that these valuations correspond with the price per pound of 30 merchandise indicated by the series of price-marks. It will thus be apparent that if a five-pound weight, for instance, be placed upon the weight-holder it will be necessary in order to determine the valuation of merchandise upon the scale to add to the price indicated by the pointer 19^a the price appearing below the numeral "5" of the numbers B' of 35 the series B. Thus if seven pounds merchandise are to be sold at the rate of five cents per pound the five-pound weight is 40 disposed upon the weight-holder 15 and the indicator 19' is moved to the two-pound mark upon the scale-arm 9, when the indicator 19^a will point to the numeral "10" upon the 45 chart, and this added to twenty-five, the

"value," so to speak, of the weight, gives thirty-five cents the cost of the merchandise. The arm 16 and poise 18 may be used for weighing under ordinary circumstances or for balancing a scoop or other vessel.

50

What is claimed is—

In a scale, the combination with a base and a standard carried thereby, of a casing carried by the standard and extending laterally therefrom and having a longitudinal opening therein, a laterally-extending loop carried by the casing, a loop engaged with the first-named loop, a scale-arm having an opening therein adjacent to its rearward end in which the second loop is pivotally engaged for vertical movement of the arm upon the loop, a rod pivotally engaged in the scale-arm rearwardly of the loop and extending downwardly therefrom, a vertically-movable platform mounted in the base, connections between the platform and the arm for simultaneous movement thereof in the same direction, a supplemental scale-arm carried by the first-named scale-arm therebelow and lying in spaced relation thereto, a poise slidably 65 mounted upon each scale-arm, a chart located within the casing, said chart having a series of characters thereon disposed in position to be seen through the opening in the casing, an indicator carried by the poise of the first-named scale-arm and arranged for indication of different characters in the series successively when the poise is slid upon the arm, said chart being movable within the casing and having additional series of characters 70 thereon arranged for movement into position for observance through the opening successively as the chart is moved, and means for moving the chart.

In testimony whereof I affix my signature 75 in presence of two witnesses.
